(57) **CLAIM**

The ornamental design for a measuring instrument housing, as shown and described.

DESCRIPTION

FIG. 1 is a top-rear-right perspective view of a measuring instrument housing, showing the design;

FIG. 2 is a front elevation view of the measuring instrument housing of FIG. 1;

FIG. 3 is a rear elevation view of the measuring instrument housing of FIG. 1;

FIG. 4 is a left elevation view of the measuring instrument housing of FIG. 1;

FIG. 5 is a right elevation view of the measuring instrument housing of FIG. 1;

FIG. 6 is a top plan view of the measuring instrument housing of FIG. 1;

FIG. 7 is a bottom plan view of the measuring instrument housing of FIG. 1;

FIG. 8 is a top-front-right perspective view of the measuring instrument housing of FIG. 1;

FIG. 9 is a top-front-left perspective view of the measuring instrument housing of FIG. 1; and,

FIG. 10 is a top-rear-left perspective view of the measuring instrument housing of FIG. 1.

1 Claim, 10 Drawing Sheets
